ROTARY SLIDE HOLDER FOR PROJECTORS

Gustav Spindler, San Francisco, Calif., assignor
to Spindler & Sauppe, a corporation of California

Application January 3, 1938, Serial No. 182,970

4 Claims. (Cl. 88—27)

This invention relates to improvements in projectors and has particular reference to a projector wherein the slides to be thrown upon the screen are automatically moved into and out of the beam of light at predetermined intervals, or, if desired, manually actuated from a revolving magazine.

The principal object of this invention is to produce a device of this character which may be attached to a standard projector, thus eliminating expensive changes to the projector.

A further object is to produce a device of this character which is simple in construction, economical to manufacture, and one which will not require attention over long periods of time.

A further object is to provide means whereby the magazine may be readily and quickly changed so as to provide for the showing of several series of pictures.

A further object is to provide means for regulating the interval during which the picture is thrown on the screen.

Other objects and advantages will be apparent during the course of the following description.

In the accompanying drawings forming a part of this specification and in which like numerals are employed to designate like parts throughout the same,

Fig. 1 is a front elevation of my device, showing the same attached to a standard projector;

Fig. 2 is a top plan view of Fig. 1, showing portions thereof broken away;

Fig. 3 is an enlarged fragmentary cross sectional view of my device, showing portions thereof in elevation;

Fig. 4 is a bottom plan view of the base plate with the motor removed and showing the parts in retracted position;

Fig. 5 is a fragmentary detailed view, showing the magazine gear lock mechanism as viewed from above;

Fig. 6 is a fragmentary detailed view similar to Fig. 4 and showing the slide actuated mechanism in advanced position;

Fig. 7 is a side elevation of the slide carrier mounting;

Fig. 8 is a top plan view of Fig. 7; and

Fig. 9 is a diagrammatic view of the wiring.

In projecting pictures upon a screen, or other receiving surface, it is customary to place a transparency within a beam of light whereby the beam projects the picture upon a receiving surface. Then it is necessary to remove this picture and insert another in the carrier, which is again moved before the beam of light. With this

type of mechanism, the operator must coordinate his efforts with a lecturer, if a lecture is being given and illustrated by the pictures. Further, there is a visible movement on the screen during the changing of the slides.

I have, therefore, devised a mechanism wherein a plurality of slides are maintained in a magazine which may be readily placed upon an actuating mechanism, after which the slides will be introduced into the projector at various intervals; and during this period of injection and removal, the light in the projector will be extinguished and relit so that there is no apparent movement visible on the screen.

In order to accomplish this object, I provide a bracket 5 which is attached to the projector, designated as a whole by the numeral 6, through the medium of thumb screws 7. Secured to the bracket 5 is a casing 8 further supported by an adjustment screw 9. Mounted upon the casing 8 is a base plate 11 which is held to the base by an annular ring 12 and screws 13. It will here be noted that this ring 12 has an extension 14, the purpose of which will be later seen. Rotatably mounted on the plate 11 is a magazine gear ring 16 which has a projection 17 underlapping the extension 14, thus holding the ring 16 on the base 11, and an upstanding pin 18 capable of entering the hole 19 formed in the magazine base 21. The plate 11 has an upstanding collar 22 which is engaged by the hooked ends 23 of the slide frames 24, the slides being shown at 26. The top of the magazine is shown at 27, and it is within the slots formed in these members 21 and 27 that the slides move. The mechanism thus far described is similar to that described in my patent, No. 2,076,924, and forms no part of this application.

My present mechanism is designed to actuate the slides into and out of the magazine and consists of a motor 28 which drives a gear 29 through reduction gearing. This gear 29 meshes with a gear 31 mounted upon a stud 32. This stud 32 also carries a multilated gear 36 which meshes with an intermittently operated gear 37 mounted on a shaft 38, which extends through the plate 11, and is provided with a single tooth 33 adapted to engage the teeth 34 of the gear ring 16. A crank arm 39 is connected to the gear 37 at one end and is pivoted a short distance from its opposite end as at 41 to a toothed segment 42, pivoted as at 43 to the underside of the plate 11. The intermittent gear 37 carries a locking segment 44 which is adapted to contact a complementary locking segment 46 formed upon

the gear 36. The cutaway portion 47 of the gear 36 permits this gear to keep on rotating during the still period of the gear 37, or during that period when the member 44 is riding upon the member 46. In other words, this movement is in reality a modified Geneva movement. The segment 42 meshes with a rack 48 carried upon the underside of the slide carrier block 49 which with the block 51 moves in tracks 52 carried on the undersurface of the plate 11. These slide carrier blocks are secured together by a spring 53, the purpose of which will be later seen. The block 49 carries a slide carrier 54 having a finger adapt'd to engage the hooked ends 23 in the same manner described in my patent, No. 2,076,924. It is understood that the slide carrier 54 extends through a slot in the plate 11. The gear 31 carries a cam 56 which is contacted by an arm 57 attached to a pivoted carrier 58 mounted upon a support 59. This carrier 58 supports a mercury switch 61, whereby when the arm 57 rides upon the cam 56, it will tip the mercury switch and break an electrical circuit. A similar mercury switch 62 has an arm 63 which is adapted to engage a cam 64 formed upon the gear 36. This mercury switch 62 also controls an electrical circuit through a timer mechanism 66. A switch lever 67 operates connections to control the time interval that the slides are viewed.

30 In order to lock the magazine against accidental rotation so that it will not be jarred out of registration with the opening in the projector into which the slide must move, I provide a magazine gear lock mechanism which consists of a peculiarly shaped lever 68, pivoted to the underside of the plate 11 and engaged by a pin 69 carried upon the free end of the crank arm 39. This pin 69 causes the lever 68 to move from the full line position to the dotted line position of Fig. 5 when the parts move from that shown in Fig. 4 to that shown in Fig. 6. As a result, a pin 71 (see Fig. 2) is moved into and out of the teeth 34 at each reciprocation of the crank arm 39. In order to prevent movement of the lever 68, except when it is in the position of Fig. 4, I provide segmental tracks 72 on the underside of the segment 42, which tracks are in spaced arcuate alignment with a pin 73 projecting downwardly from the lever 68. Therefore, when the parts are in the position of Fig. 4, the pin 69 will cam upon the surface A (see Fig. 5) and push the lever 68 in such a direction as to remove the pin 71 from the tooth of the gear 16, so that the gear 16 may be moved one notch to bring a new slide into proper alignment. As soon as the pin 69 has left the cam surface A, the pin 73 will again be in proper position to be engaged by the tracks 72, and, therefore, the pin 71 will be held locked in the teeth 34.

60 The result of this construction is that when the machine is assembled as shown and it is desired to project pictures upon a screen, the operator closes the switch, diagrammatically illustrated at 74 in Fig. 9. As a result, current is delivered from the line to the motor 28, which motor drives the gear 31 and its attached gear 36. At the beginning of the cycle the parts will be in the position of Fig. 4. Consequently, the rotation of the gear 36 will cause rotation of the gear 37, movement of the crank arm 39, movement of the segment 42, rack 48, slide carrier blocks 49 and 51, and the slide carrier 54. As the slide carrier moves forwardly, a slide is moved into the projector. At the same time, as the segment 42 moves from the position of Fig. 4 to

that of Fig. 6, the tracks on the underside of the segment 42 will move over the pin 73 of the lever 68, thus locking this lever 68 against pivotal movement, with the result that the pin 71, projecting through the plate 11, will be held in the teeth 34 of the gear ring 16, and the magazine, which is resting upon this gear ring 16 and pinned thereto, will be held against any possible misalignment. As soon as a slide has reached the position within the projector, the mercury switch 62, which is a double pole switch, is actuated by the arm 63 being engaged by the cam 64, and the bulb in the projector is illuminated. At the same time, the motor 28 is cut out, leaving all parts at rest. However, there will be a slight inertia to the motor, and, therefore, by mutilating the gear 36, this continued movement of the motor will not effect movement of the gear 37. The timer mechanism 66, however, is operating and finally completes a circuit through brushes B, (see Fig. 3) wherein power is again switched on to again start the motor. As the gear 36 and its attached gear 31 are rotated further, the arm 63 will move off the cam 64, and the light will be extinguished. The motor will continue to function until the locking member 44 leaves the complementary locking segment 46 and the teeth of the gears 37 and 38 again mesh, resulting in the gear 37 through the crank arm 39 returning the segment 42 to its starting position. It may be here explained that when the slide carrier 54 reaches its innermost position, the slide carrier block 49 is stopped, and the slide carrier block 51, to which the rack 48 is attached, continues a short distance, which is permitted through the action of the spring 53. It is during the short interval that the slide carrier block 51 parts from the slide carrier block 49 that the magazine is moved sufficiently to bring a new slide into position, and this is accomplished by the tooth 33, carried upon the shaft 38 to which the gear 37 is attached, engaging one of the teeth in the gear 16 upon which the magazine is resting. Also, at this time, the pin 69 moves the lever 68 so as to move the pin 71 into the position of Fig. 2, thus unlocking the gear 16 so that it may be moved the required distance. This completes one cycle of operation. However, should a person turn off the switch 74 during the time that a slide is in the projector, the mercury switch 61 will be in such a position as to hold the current on the motor and timer mechanism to complete the cycle of operation, which will be completed when the arm 57 rides upon the cam 56, thus moving the mercury switch 61 to off position.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a device of the character described, the combination of a projector, a casing structurally related thereto, a horizontally disposed base plate on said casing, a ring gear on said base plate, a rotatable slide magazine detachably mounted on said ring gear and said base plate, driving pins secured on said ring gear and extending upwardly into holes in said magazine to form a driving connection for said magazine when said ring gear is rotated, a one-toothed gear and driving means for rotating said ring gear in steps of one tooth at a time, and driving means including inter- 75

mittent gears and cams for intermittently moving said ring gear and said magazine to successive positions and for moving slides into and out of projecting position.

5 2. In a device of the character described, the combination of a projector, a casing structurally related thereto, a longitudinally disposed base plate on said casing, a ring gear on said base plate, a rotatable slide magazine detachably mounted on said ring gear and said base plate, driving means connecting said ring gear and said magazine, whereby said magazine and said ring gear will be simultaneously moved, a slide carrier for moving slides from said magazine into 10 projecting position and withdrawing said slides into said magazine, slide carrier blocks on said base plate and supporting said carrier, a rack connected to one of said slide carrier blocks, spring means for connecting said blocks one to the other, a toothed segment engaging said rack, 15 cam means for intermittently moving said segment, and a locking pin intermittently engaging the teeth of said ring gear during projection.

3. In a device of the character described, the combination of a projector, a casing structurally related thereto, a base plate, an annular ring gear on said base plate, a magazine removably positioned on said base plate, a locking pin lever pivotally mounted beneath said base plate and having a pin extending therethrough, whereby 20 said pin may enter the teeth of said ring gear,

an intermittently actuated crank engaging said lever to move said pin into and out of the teeth of said ring gear, a slide moving means structurally in cooperation with said magazine and comprising a slide carrier mounted on said base plate, a segment mounted on said plate and having driving connection with said carrier and said crank, and driving means for intermittently actuating said crank. 5

4. In a device of the character described, the combination of a projector, a casing structurally related thereto, a base plate, an annular ring gear on said base plate, a magazine removably positioned on said base plate, a locking pin lever pivotally mounted beneath said base plate and having a pin extending therethrough, whereby 15 said pin may enter the teeth of said ring gear, an intermittently actuated crank engaging said lever to move said pin into and out of the teeth of said ring gear, a slide moving means structurally in cooperation with said magazine and comprising a slide carrier mounted on said base plate, a segment mounted on said plate and having driving connection with said carrier and said crank, and driving means for intermittently actuating 20 said crank, and arcuate tracks carried by said segment and engaging a pin on said lever, whereby said lever will be locked against movement during the reciprocation of said segment. 25

30 GUSTAV SPINDLER.
